MACHINE FOR MAKING AND DRIVING
CORRUGATED FASTENERS

John Sherman McChesney, Chicago, Ill.; Lula A. McChesney, executrix of said John Sherman McChesney, deceased, assignor to Lula A. McChesney

Application September 9, 1932, Serial No. 632,338

40 Claims. (Cl. 1-9)

The present invention is an improved power driven automatic machine for producing finished corrugated fasteners from strip metal or ribbon without removal of metal in the making 5 thereof, and thereafter to drive cut to length corrugated fasteners.

One of the objects of the present invention is to produce from a single ribbon or strip of metal, through a continuity of operations, employing combined, co-acting, opposed, rotary swaging and slitting rolls, said operations performed without the removal of metal in the simultaneous forming of two opposingly faced penetrating edges and thereby producing two 15 sharpened severed strips; each severed strip having a relatively blunt driving end and a smooth, compressed, work hardened, continuously beveled, sharp cutting, penetrating end; V shaped when viewed in end section, said penetrating end may be of scalloped, or of saw-toothed, or of plain edged formation; thereafter, simultaneously to pull, to corrugate and to feed, to sever, and to drive the completed severed corrugated fastener into wood or other material 20 for such general purposes as the splicing of shocks, box ends, knots, splits, basket bottoms, sash, doors, columns, furniture, wood novelties and the like.

Other objects are to obtain without the removal of metal in the forming of the penetrating end of the fastener thru a sequence of rotary swaging operations upon a smooth flat metal strip or ribbon, adapted to the manufacture of corrugated fasteners, having the required gauge, temper and the width to produce when severed longitudinally intermediate the blunt side edges thereof, two strips of flat sharpened fastener stock; each of said severed strips provided with a blunt driving end, a compressed, 30 smooth beveled, continuous sharp cutting penetrating end, V shaped when viewed in end section; thereafter to pass the sharpened flat strips to and between combined power driven co-acting, pulling, corrugating and feeding rolls; 35 thereby simultaneously to pull and to advance said strips lengthwise, to corrugate substantially crosswise, i. e., to continuously bend and rebend the metal so as to form corrugations extending alternately on each side of the central or medial 40 plane of the resultant fasteners; and thereafter, to feed said corrugated fastener stock into co-acting fastener severing means and thereafter into fastener driving means, in and after the manner employed in sheet metal fastener 45 driving machines.

More specifically stated, in the machine of my invention I employ a flat, smooth metal ribbon or strip of such commercial width and tolerance, gauge and temper as to simultaneously produce from said strip, two strips, each of said strips having a sharp cutting, beveled penetrating end formed thereon without removal of metal in machining by a rotary metal compressing and slitting process, resultant of a continuous, smooth surfaced, knife edged, beveled penetrating end, V shaped when viewed in end section. The machined metal of the penetrating end of the fastener intermediate the V, of greater density and therefore of greater hardness than the non-beveled metal of the fastener 15 strip; thereafter, the terminal ends of the severed sharpened strips pass to and between my new and improved form of mated gear driven, co-acting, combined, pulling, corrugating and feeding rolls, wherein the sharpened strip is 20 simultaneously pulled into and passed through and fed out of the corrugating rolls in the direction of its length, is thereby continuously corrugated by bending and rebending to produce corrugations of parallel formation or of divergent 25 formation as desired. Thereafter, one or both of the sharpened corrugated strips may exit the machine to be coiled on a reel, or one or both said strips may be fed into a companion corrugated fastener driving heads, thereby to 30 produce a duplex head corrugated fastener making machine.

The machine may be operated without the fastener driving mechanism functioning and the completed cut to length fastener may be hand 35 hammer driven; or operated without the fastener corrugating, severing and driving mechanism, the sharpened flat fastener stock may be assembled exterior of the machine into coils wound on suitable cores containing several hundred feet to the coil.

Commercially, corrugated fasteners in coils are sold by weight, a matter which is of importance in the consideration of the object of my improved method of making corrugated 45 fasteners; in that, among the new novel and outstanding features in the manufacture of the corrugated fasteners of my invention I produce simultaneously from a single strip of metal by a combined severing and compressing process, 50 two strips, each strip having a knife edged penetrating end, V shaped when viewed in end section, susceptible of a wide range of profile formations such as "scalloped", or "saw tooth", or modifications thereof, or "plain edge" forma- 55

tion; all machined without removal of metal in the making of the penetrating end of the fastener and, therefore, without loss of weight in the manufacture of the completed fastener directly 5 from the metal strip or ribbon. In the prior art the penetrating end of each corrugated fastener is formed individually and separately by a milling, shearing, or grinding process in the production of each fastener strip thereby resulting in 10 an appreciable loss of time, and of weight of metal, when compared with the manufacture of fasteners of my invention.

Another salient feature of my invention is the obvious fact that the width of the original flat 15 metal strip when measured at right angles to the parallel side edges, is of lesser width than the combined added widths of the two resultant beveled strips simultaneously formed therefrom in accordance with the process and procedure 20 disclosed in the production of the corrugated fasteners of my invention, when similarly measured between the driving edge and extreme penetrating edge thereof. In other words, the combined width of the two resultant simultaneously 25 formed severed strips in both the "saw edged" and "plain edged" type of fastener, measured from the extreme driving edge and at right angles thereto, to the extreme penetrating edge of each fastener strip, is greater than the distance 30 similarly measured between the parallel side edges of the original strip.

In machines of the prior art the penetrating edge of the fastener is formed singly and is accompanied by the removal of metal from the 35 strip either before or after corrugating, thereby representing an appreciable loss of metal whereas in the machine of my invention I produce two penetrating edges simultaneously without removal of metal. In commercial practice, 40 cut to length fasteners are designated by number, the number referring to the number of corrugations to each fastener and by the distance between the extreme penetrating and driving end, fasteners thus described are sold by count; 45 therefore, it is obvious that in the machine of my invention I produce a greater number of fasteners from a given surface area of material by forming the penetrating end by the method and procedure herein disclosed in which I employ 50 combined metal compressing and metal severing or slitting means, wherein the metal of the beveled penetrating end is compressed and forced outwardly in such manner as to increase the plan surface area in excess of the original 55 plan area of fastener strip or ribbon.

For the broader purpose of my invention such a machine may or may not contain the means for doing the driving, may or may not contain the means for doing the severing, or may or may 60 not contain both the means for doing the driving and the severing; and, on the other hand, if it contains the penetrating edge forming means and corrugating means, then, and for the broader purpose of my invention it may or may 65 not contain the means for cutting off and driving the fastener. In other words, the combination of means for automatically forming the beveled penetrating end without removal of metal; combined means for simultaneously and automatically pulling corrugating and feeding two simultaneously sharpened strips formed from one strip, and severing means and driving means, is new with me. Preferably, however, the machine includes means for rotatably impressing or swaging 70 opposingly into the flat side surfaces inter-

mediate the side edges thereof, of a metal strip, a compressed, work hardened, continuously beveled, knife edged, sharp cutting penetrating ends, substantially of X shaped appearance when viewed in end section before complete severance, 5 and V shaped when viewed in end section after severance; means to return upset metal within the body of the strips, means then simultaneously pull said sharpened strips into, and thru co-acting, mated, registered, corrugating rolls, thereby to corrugate said sharpened strips relatively crosswise, to advance a said corrugated strip in the direction of its length; for then cutting off a length of such transversely corrugated strip, and for then driving the finished 10 fastener into the wood or other material in the general direction of the corrugations either with or across the grain of the wood.

The series of machine operations herein described provides for the rapid and economical 20 manufacture of the new fastener in combination with a fastener severing and driving machine. The fastener as an article is free from burrs, is uninterruptedly beveled throughout its longitudinal length at the penetrating end thereof, the 25 intersecting planes of the bevels meet intermediate the longitudinal side edges of the strip, resulting in a continuous sharp cutting penetrating edge.

The resultant article of manufacture comprising 30 a corrugated fastener herein shown and described as the product of the machine, constitutes in part the subject matter of my co-pending application No. 615,512.

In the accompanying drawings forming a part 35 of this specification I have shown a preferred form of my invention and described same in detail in the following specification. It is to be understood, however, that the specific disclosure herein is for the purpose of exemplification only 40 and that the scope of the invention is defined in the following claims.

My invention is illustrated more or less diagrammatically in the accompanying drawings 45 wherein—

Figure 1 is a perspective front view partly in section of so much of a corrugated fastener making and driving machine as is necessary for the understanding of my invention.

Fig. 2 is a sectional diagrammatic plan view 50 taken partly on line 2—2 of Fig. 1, illustrative of the progress of the metal strip thru the strip positioning guides; penetrating edge forming rolls; upset metal flattening and feed rolls; combined pulling, corrugating and feeding rolls; 55 fastener severing and driving mechanism, power driven ratchet actuated mechanism, exit guides and fastener coil.

Fig. 3 is a front elevation of co-acting swaging rolls adapted to impart registered saw-tooth 60 formation to a metal strip shown in section intermediate the working faces of the rolls.

Fig. 4 is a bottom perspective side view on an enlarged scale of saw-toothed corrugated strip with saw-toothed points in a random position with respect to the medial plane of the fastener.

Fig. 5 is a bottom perspective side view on an enlarged scale of saw-toothed corrugated strip, 70 with saw-toothed points alternately positioned in substantially parallel relation along lateral edges of the fastener and on the crests thereof.

Fig. 6 is a bottom perspective side view of an enlarged scale of saw-toothed corrugated strip 75

with saw-toothed points positioned substantially in the medial plane of the fastener.

Fig. 7 is a bottom perspective side view on an enlarged scale of a plain edged beveled corrugated fastener formed by the roller swaging action after the manner illustrated in Fig. 1, Fig. 8, Fig. 16, Fig. 23, and Fig. 24.

Fig. 8 is a fragmentary view on an enlarged scale, of a flat metal strip shown in section undergoing beveling operation intermediate opposed rotary swaging rolls.

Fig. 9 is a fragmentary view on an enlarged scale illustrating the action of returning into the strip the up-set metal of the partly beveled and partly severed fastener strip.

Fig. 10 is a perspective diagrammatic view of presharpened fastener strips intermediate mated combined, pulling, corrugating and feeding rolls and in combination with fastener severing and driving means and roll actuating mechanism.

Fig. 11 is a view in elevation of combined pulling, corrugating and feeding rolls, wherein is represented the development of the parallel corrugating roll and resultant corrugated fastener strip in combination with a divergent corrugating roll and development of resultant divergent corrugated fastener strip.

Fig. 12 is a front elevation partly broken away of resultant progressive steps in producing two severed, compressed, beveled plain edged strips of pre-sharpened fastener stock from one strip of metal.

Fig. 13 is a front elevation partly broken away of resultant progressive steps in producing two saw-toothed beveled edged strips of pre-sharpened fastener stock from one strip of metal.

Fig. 14 is a fragmentary enlarged perspective front view taken on line 14-14 of Fig. 13 indicating in shaded lines the area of compressed, work hardened metal, positioned intermediate the X of the beveled portions of the strip.

Fig. 15 is an end view partly in section taken on line 15-15 of Fig. 2 of gear driven flat cylindrical upset metal reducing rolls and connected actuating mechanism.

Fig. 16 is an end view partly in section taken on line 16-16 of Fig. 2 of mated gear driven swaging rolls adapted to impart V shaped plain edged formation to a metal strip shown in section intermediate the working faces of the rolls, interchangeable with registered saw-tooth penetrating edge forming rolls of Fig. 3 and connected actuating mechanism.

Fig. 17 is an enlarged plan view of the completed severed saw-toothed divergent corrugated fastener, the teeth placed in random position with respect to the medial line of the fastener.

Fig. 18 is a plan view of the penetrating edge of same.

Fig. 19 is a perspective view of co-acting fastener severing mechanism, illustrative of two simultaneously severed plain edged fasteners of equal length and unequal width.

Fig. 20 is a perspective view of metal strip positioning guides.

Fig. 21 is an enlarged plan view partly broken away of castellated beveled saw tooth formation of the penetrating edge.

Fig. 22 is an enlarged plan view partly broken away of scalloped beveled saw tooth formation at the penetrating edge.

Fig. 23 is an enlarged view partly in section and partly in elevation of a metal strip illustrative of the area of contact between the rotat-

ing disc and bevel of the metal strip and the severing compressing action of the combined rotary co-acting, swaging and severing discs prior to separation of the strip into two beveled strips.

Fig. 24 is an enlarged view partly in section and partly in fragmentary elevation of a metal strip, co-acting rotary swaging and slitting discs illustrative of clearance angle of rotary rolls employed in the successive operations of forming sharp, knife like cutting edge of the penetrating end.

Like parts are designated by like characters throughout the specifications and drawings.

Referring to Fig. 1, representative in part, of a commercial form of corrugated fastener feeding, severing and driving machine, to which I have added parts embodying the principle of my invention. The hollow pedestal A, supports a housing partly open and partly closed comprising a frame A¹, the form of which is immaterial it being only essential that it serve as a firm and rigid mounting for the power actuating mechanism and associated parts therein contained, in suitable elevated position.

To operate the machine, pressure on the foot operated clutch release treadle A² releases a one revolution clutch pin A³ effecting engagement between the power driven fly wheel A⁴ and the operating shaft B causing same to rotate thru one complete revolution. The operating shaft B is mounted in the hollowed out enclosed portion of housing frame A¹, in suitable bearings A¹⁰.

Reference being had to Fig. 10, a combined crank plate and enclosed cam B¹ integral with the operating shaft B, enclosed in the hollowed out portion of the housing frame A¹, and positioned rearwardly of the housed fastener driving head A⁵, functions to impart timed reciprocal straight line motion to a co-acting fastener strip severing knife K² thru a pin connected rocker arm K³ pivotally mounted on shaft K⁴ and provided with cam roller K⁵ which contacts the enclosed cam surface of B¹. A crank pin B⁶ functions thru a pitman B⁷ which transmits reciprocal straight line motion to an overhead rod B⁸, which in turn imparts an up and down motion to housed fastener driving head A⁵ and to its attached fastener driving blade A⁹.

To the reciprocating overhead rod B⁸ is fixedly attached an extension arm B⁹ which in turn imparts motion thru a connecting link B¹⁰ to a pawl carrying arm B¹¹ loosely mounted on a worm drive shaft F¹ and contacting with a ratchet wheel F² secured to the outer end of the worm shaft F¹ and contacting a ratchet engaging pawl B¹² loosely secured on the arm B¹¹ by pin B¹³. A conventional cam release B¹⁴ pivotally mounted on pin B¹⁵ secured to the frame A¹ functions to regulate the length or arc of engagement of the pawl B¹² with the ratchet wheel F², so to limit and to regulate intermittent rotation of the ratchet operated shaft F¹.

Reference being had to Fig. 2, the shaft F¹ mounted on suitable support F¹⁰ on the frame A¹ is shown in part and broken away, functions to rotate in unison thru a train of gears all of the opposed connected roller mechanisms positioned on frame A¹. Attached to the shaft F¹ is a series of helical gears F² meshed with corresponding small helical gears F³, as in Fig. 2, Fig. 10, Fig. 15 and Fig. 16, fixedly attached to the stub end of the adjustable roller receiving and drive shaft F⁴; immediately above, is fixedly attached a spur gear F⁵ meshed with a like

spur gear F^4 fixedly attached to the stub end of the roller receiving and driving shaft F^5 .

The shafts F^4 and F^5 are adapted to receive the key secured strip manipulating rollers of various types, such as are shown in Fig. 1, Fig. 2, Fig. 3, Fig. 10, Fig. 15, Fig. 16, Fig. 23 and Fig. 24 and modifications thereof. Up and down timed movement of the bar B^4 , actuated as described, causes all of the penetrating end forming rollers S ; combined upset metal flattening and feed rollers U ; the combined upper paired corrugating roller C^1 and corresponding lower paired corrugating rollers C^2 to rotate in a direction to advance the strip R to and thru strip 10 positioning guides G^1 spaced at intervals in advance of and intermediate of the paired, penetrating end bevel forming rollers S of the "plain edge" type of fastener, or S^1 of the "saw tooth" type of penetrating end forming roller; there- 15 after thru upset metal flattening rollers U ; thence, thru coating combined pulling, corrugating and feeding rollers C^1 and C^2 , then into the path of fastener driving means; the fastener severing means in cam timed relation 20 to the aforescribed means.

The machine as illustrated is adapted to impart a variety of tooth formations to the penetrating end of the fastener, i. e., to produce corrugated fasteners of the type known to the 30 trade as "plain edge" corrugated fasteners, shown in Fig. 7, Fig. 10 and Fig. 19 and in the uncorrugated sharpened strip form, as in Fig. 12, or of the "saw tooth" type of corrugated fastener as in Fig. 4, Fig. 5, Fig. 6, Fig. 11 and 35 Fig. 17 and in the uncorrugated sharpened strip form in Fig. 13, Fig. 21, and Fig. 22. A wide variety of beveled tooth form swaging rollers may be substituted for the two general types of rollers S^1 and S^2 herein shown without departing 40 from the spirit of my invention.

The beveled penetrating end forming swaging rollers, assembled as shown in Fig. 3 and Fig. 16, are mounted in any suitable form of bearings so that the paired swaging rollers mounted on 45 the drive shafts F^4 and F^5 are held in pre-determined registered mated position, in such manner that the gear driven shaft F^5 is held in fixed bearings in the frame A^1 and the gear driven shaft F^4 is held in screw pressed adjustable bearings F^6 , actuated by pressure screws F^7 , which 50 permit spaced adjustment of the cutting edges S^1 of the penetrating edge forming rollers to the desired distance. The safe minimum allowable distance between the rollers is permanently 55 maintained by safety lands S^2 on each of the opposed rollers, said lands functioning by surface contact to prevent the bevel forming cutting edges S^1 of the roller from contacting, thereby to destroy the sharp cutting beveled 60 edges thereof. Any suitable form of vertical aligning device may be employed such as interlocking grooves S^3 to maintain alignment and register of the cutting edges S^1 .

The method of producing the fastener is as 65 follows:

Any suitable material may be employed in the manufacture of the fastener, but preferably a smooth, flat metal strip R adapted to the manufacture of corrugated fasteners of the required 70 gauge, temper and of a width to produce, when simultaneously opposingly swaged and severed, two sharpened strips R^1 and R^2 , each strip having a blunt driving end and a knife like penetrating end, each of said strips of a predetermined width. The strip R initially enters into

and is pulled thru the machine from the entering end E of the partly open portion of the frame A^1 , thereafter passes progressively thru one or more sets of strip receiving and positioning guides G^1 , shown in perspective in Fig. 20 and in sectional plan view in Fig. 2. Any desired form of guide may be used to maintain the strip in position to be acted upon by strip manipulating rolls. The guides function to maintain the longitudinal axis and the medial plane of the strip R in such fixed predetermined position with respect to the opposed bevel forming edge S^1 of the swaging rolls, that when acted upon by swaging rollers initially forms the penetrating end of the fastener R^4 and the cutting edge R^4 as shown in Fig. 12 in the "plain edge" type of fastener, and in Fig. 13 in fastener of "saw tooth" penetrating edge formation; and is also indicated in perspective in Fig. 1 and in top plan view in Fig. 2.

The resultant longitudinally severed strips R^1 and R^2 may be of equal width or of unequal width as determined by the positioning of the guides G^1 with respect to the edge S^1 of the swaging rollers S . The strip may be wholly divided by the first set of combined penetrating edge forming and slitting rollers into two beveled sharpened strips, R^1 the upper strip, and R^2 the lower strip, or may pass successively thru one or more sets of combined penetrating end forming 25 and slitting rolls in such arrangement as shown in Fig. 1 and Fig. 2 wherein the strip R is simultaneously beveled in register on its opposed longitudinal sides by the beveled forming and slitting edges S^1 , each pass advancing the beveled 30 cutting edges S^1 of the opposed rolls to greater depth within the strip until severance is completed, thereby producing strips R^1 and R^2 .

During the beveling operation, upset metal S^4 of more or less prominence is thrown up at the 40 outer surface edge of the beveled faces as shown in Fig. 8. The upset metal is returned into the metal of the strip by flat surfaced opposed combined strip pulling, feeding and flattening rollers U , shown in Fig. 1, Fig. 2, Fig. 9 and Fig. 15 45 adapted to return the upset metal S^4 into the body of the strips R^1 and R^2 , thus reducing the strip to its original thickness, and simultaneously to advance the strip metal in the direction 50 of its length.

The narrow side edges of the strip R in its initial form, are the blunt driving ends R^3 of the severed beveled strips R^1 and R^2 . During the forming of beveled sides of the penetrating end R^4 the metal intermediate the sides is compressed thru the area as is indicated by the darkened shaded sections in Fig. 8, Fig. 9, Fig. 12, Fig. 13 and in the enlarged sectional views of Fig. 14, Fig. 23, and Fig. 24. It will be seen that the penetrating end of the fastener is substantially of X shaped appearance when viewed 60 in end section before severance, and V shaped when viewed in end section after severance, thus the cutting edge R^4 is formed by the meeting of the planes of the beveled surfaces intersecting 65 intermediate the longitudinal side edges, the sharp cutting edge R^4 is continuous throughout the length of the fastener strip in both the uncorrugated and corrugated state.

The beveled surfaces S^1 of the penetrating end 70 forming rolls S and substitute rolls S^1 contact and enter into forced, opposed, rolling and sliding contact with the metal of the strip R during the forming of the smooth, beveled, compressed, penetrating ends of the strips R^1 and 75

R'. The fixed distance between the cutting edges S¹ is capable of being maintained thru lands S² or by any other desired form of positive roll separating means, so that, during the progress of the strip R thru one set or thru successive sets of penetrating end forming rolls the cutting edge of the roll S¹ may be caused to successively advance and force its way into the metal of the strip up to the point of severance. 5
 10 In practice there is a noticeable tendency for the metal of the strip R to rupture during manipulation and leave a ragged penetrating edge R' of appreciable width, due to the side pressure of the beveled moving surfaces of the penetrating edge forming rolls contacting the formed beveled side of the embryonic penetrating edges of the metal strip R, thereby creating excessive side pressure on the strips R¹ and R² sufficient to cause the metal intermediate the cutting edges 15
 20 S¹ to rupture before the completion of the slitting operation, as is obvious and as is clearly apparent from Fig. 23. In the machine of my invention I employ a series of opposed combined beveled swaging and slitting rolls in which the included angle of the opposed beveled surfaces of the rolls is progressively decreased so as to reduce side contact between the bevel of the rolls and the metal of the strip R, thereby permitting the cutting edges S¹ to function to produce the hard, sharp cutting, knife like, swaged cutting edge R' of the penetrating end on each severed strip R¹ and R² as indicated in Fig. 24 without 25
 30 rupture of the metal to an extent to effect the sharp cutting properties essential to the penetrating edge of the fastener.
 35 The cutting edge R' of the strip R¹ faces the table A' which supports the material A⁶ in which the fastener is to be driven and the cutting edge R' of the strip R² is oppositely faced.

40 The sharp cutting severed strips R¹ and R² next enter into and are pulled thru, respectively, an upper pair and a lower pair of gear driven combined mated co-acting pulling, corrugating and feeding rollers; of which paired rollers C¹ engages strip R¹ and paired rollers C² engages strip R², said rollers acting to bend and rebend the sharpened metal strips R¹ and R² to produce transverse corrugations therein and to simultaneously advance the now corrugated strips R¹ and R² thru the corrugated fastener guide plates G³, at the knife end of which is mounted a spring pressed stripper K placed slightly in advance of and functioning to guard the cutting edge of the stationary co-acting severing knife K¹, during the advance of the corrugated strips into the line of the driving head A⁶. The cutting edges of the knives K¹ and K² are of greater width than the strips R¹ and R². It is, therefore, apparent that the strip R¹ crosses the path 55
 60 of the co-acting severing knives K¹ and K² and enters the spring pressed, severed fastener retaining guides G³, in position to be driven home by the fastener driving blade A⁹. The strip R² may be shunted to move within the exit guides G⁴ and thereafter be guided exterior of the machine into a fastener severing and driving head thereby forming duplex fastener driving heads, or it may be accumulated in coiled form 65
 70 as is indicated by R⁵ of Fig. 2. The forward movement of the strips R¹ and R² may both be directed within the guides G³ in such manner that the co-acting severing knives K¹ and K² function to form cut to length corrugated fasteners R' which exit the machine thru the space 75

otherwise occupied by the then disconnected elements A⁵ and G².

Briefly stated, in the machine of my invention one complete rotation of the operating shaft B advances the strip R, by a step by step movement, a predetermined distance thru strip positioning guides G¹; penetrating end swaging, beveling and severing rollers S, functioning to form two severed sharpened strips R¹ and R² with oppositely opposed penetrating edges R'; thru 10 upset metal flattening and feeding rollers U which returns the upset metal S⁴ within the stock surface; thru co-acting paired pulling, corrugating and feeding rollers wherein both strips R¹ and R² are corrugated and advanced in the 15 direction of their length; thru corrugated fastener severing means K¹ and K², wherein strips R¹ and R² may both be severed to produce cut to length fasteners R', as shown in Fig. 19, or the strip R² may proceed thru the fastener severing 20 and driving means and in the absence of material A⁶ be discharged as completed cut to length fasteners on the table A', and the strip R² exit the machine thru the guides G⁴.

The machine is adapted to produce fasteners 25 of the "plain edged" type as shown in Fig. 7 and of the "saw-tooth" type in a wide variety of tooth forms as indicated by Fig. 17, Fig. 19, Fig. 21, and Fig. 22 and in various combinations of corrugated tooth arrangements as in Fig. 4, 30 Fig. 5, and Fig. 6. Fasteners of parallel and divergent corrugations may be produced simultaneously as is illustrated in Fig. 11 by co-acting corrugating rollers C¹ and C² wherein two strips are simultaneously corrugated, the strip R¹ having parallel corrugations and the strip R² having divergent corrugations.

A parallel arrangement and a divergent arrangement of the plurality of sets or series of ridges and the accompanying depressions appearing on the periphery of the mated corrugated rollers, illustrated in Fig. 11, are well known to the prior art. I claim as new with me the combination of arrangement wherein one strip R is simultaneously divided into two sharpened strips 45 R¹ and R², and thereafter simultaneously corrugated and thereafter severed, as herein disclosed, described and illustrated.

It will be seen that the two smooth pre-sharpened strips R¹ and R² entering respectively 50 the corrugating rollers C¹ and C², will be parallel corrugated by the upper roller C¹ and divergently corrugated by the lower roller C² and both strips will issue without being diverted from the straight line of travel as fed into the rollers for 55 the strip is not shortened by the corrugations any more towards the one edge than towards the other. Hence, the corrugated strips are delivered indefinitely in shape to be wound one upon itself and to form a compact coil of cylindrical contour as shown at R⁵ of Fig. 2, or the strips may be simultaneously advanced into corrugated fastener severing means in which both strips are severed into cut to length corrugated 60 fasteners, R' as in Fig. 19 or advanced into fastener driving means, one strip R¹ in frame A¹ and the companion strip R² exits thru guides G⁴ of the frame A¹ of the machine, into exterior related fastener severing and driving means not 65 shown, but similar in all respects to the fastener severing means and the fastener driving means of Fig. 1, Fig. 2, and Fig. 10.

Referring to Fig. 14, the embryonic beveled penetrating ends R⁶ indicated by the darkened 70

shaded section produced by compressing the metal of the strip R during the swaging operations, is obviously of greater density as a result of the squeezing or compressing thereof, is therefore, of greater work hardness than the adjacent metal. It is apparent that the fasteners of my invention, the penetrating end of which is formed by a swaging process, are obviously better adapted to be automatically power driven and to withstand abuse of driving and therefore better adapted to cut their way into hard material such as knots, cross grain, etc., than fasteners made by a shearing or grinding process and having non-compressed, non-hardened penetrating edges.

The strip metal is advanced in the direction of its length toward the fastener driving end of the machine by a step by step movement imparted by the up and down movement of the pawl carrying arm B' and the ratchet engaging pawl B² contacting the ratchet wheel F. The distance advanced by the strip on each complete revolution of the operating shaft B is controlled by a cam release B¹⁰ contacting the surface of the ratchet engaging pawl B² to limit the movement by withdrawing the engaging point between pawl and ratchet wheel. Any suitable timing arrangement may be employed.

I claim:

30 1. In a machine for making corrugated fasteners from metallic ribbon, the combination of cooperating swaging means for first severing said ribbon into two strips each strip having a swaged beveled sharp-cutting penetrating edge 35 requiring no further sharpening treatment, means comprising safety lands for maintaining the opposed bevel-forming cutting edges of said swaging means short of contact, corrugating means for then forming transverse corrugations in one of said sharpened strips, and means for then severing a suitable length of said sharpened corrugated strip.

2. In a machine for making and driving corrugated fasteners made from a metal strip, the 45 combination of swaging means for progressively severing and forming from one metal strip simultaneously two beveled strips providing each strip with a swaged beveled sharp-cutting penetrating edge, corrugating means for then forming transverse corrugations in the sharpened strips, severing means for cutting off a suitable length of sharpened corrugated strip, driving means for driving the severed completed corrugated fastener edgewise in a direction to 50 insert the corrugations thereof endwise.

3. In a machine for making and discharging corrugated fasteners made from metallic ribbon, the combination of means for swaging and slitting a metallic ribbon simultaneously into 60 two beveled strips each strip having a swaged beveled sharp-cutting penetrating end, corrugating means for forming transverse corrugations in the sharpened strips, means for cutting off a suitable length of the sharpened corrugated strips, means for discharging the severed completed corrugated fasteners edgewise exit the machine and operating connections by which the swaging and corrugating, cutting and discharging operations are performed on 65 the ribbon and on each of the strips in the order mentioned.

4. In a machine for making and driving corrugated fasteners made from metallic ribbon, comprising mechanism for guiding metallic ribbon in swaging relation with swaging dies there-

by producing two metallic strips having beveled knife-like penetrating edges, mechanism for transversely corrugating said strips, mechanism for advancing and guiding one of said corrugated strips into cutting relating with co-acting severing knives for cutting off a suitable length of the corrugated strip thereby forming a cut to length corrugated fastener, mechanism for driving said cut to length fastener, and guiding means for guiding the unsevered strip 10 exterior of the machine.

5. In a machine for making corrugated fasteners, the combination of rotatably mounted co-acting mated swaging rolls having the opposed cutting edges thereof in register and 15 maintained short of contact, said rolls adapted to swage and sever a metallic ribbon into a plurality of strips each strip having a continuous sharp-cutting swage-beveled penetrating edge said beveled edge impressed into the ribbon and 20 the ribbon severed into strips without the removal of metal therefrom, mechanism for advancing the strips forwardly in the direction of their length thru corrugating mechanism for transversely corrugating said strips, fastener 25 severing mechanism comprising co-acting cutting knives for severing lengths from one of said transversely corrugated strips, driving mechanism for engaging the blunt end of said corrugations to drive said finished fastener edge- 30 wise exit the machine, a shaft for operating said advancing swaging corrugating severing and driving mechanism, means for guiding the said metallic ribbon to said swaging means and for thereafter guiding the said strips in the direction of their length to the said corrugating mechanism and thereafter guiding one of said strips into cutting and driving relation with severing and driving means, and means for varying the number of corrugations of each finished 40 fastener.

6. In a machine for making corrugated fasteners from metallic ribbon, the combination of rotatably mounted coacting swaging and slitting rolls for producing a sharp swage-beveled edge 45 on one edge of each of the resultant strips without the removal of metal in the swaging and slitting thereof, corrugating and feeding mechanism for corrugating said strips transversely and for advancing said corrugated strips forwardly in the direction of their length, fastener 50 severing mechanism comprising co-acting cutting knives for cutting off lengths of one of said transversely corrugated strips, driving mechanism for engaging the blunt ends of said corrugations to drive individually each finished corrugated fastener edgewise and in a direction to 55 insert the corrugations endwise, a shaft for operating said driving cutting corrugating and swaging mechanism, means for guiding the said metallic ribbon to said swaging means and means for thereafter guiding said strips to said corrugating cutting and driving means, and means for varying the length of said fastener.

7. The combination with devices for oppos- 65 ingly swaging a metallic ribbon into strips, each strip having a sharp hardened beveled penetrat- 70 ing edge, of devices for corrugating said strips, of devices for cutting one of said strips into suitable lengths thereby forming cut to length corrugated fasteners, of guide means for advancing the other of said strips exit the machine for assembly in coil form, of devices for driving the severed fasteners successively into wood in the line of their corrugations and a sin- 75

gle combined crank plate and cam for operating said devices.

8. In a machine for making corrugated fasteners from metallic ribbon, the combination of co-acting swaging devices for swage-beveling and slitting a metallic ribbon into beveled serrated edged strips, of co-acting corrugating devices for corrugating said strips, of co-acting devices for subsequently severing said strips into suitable lengths thereby forming fastener plates of predetermined dimensions, of co-acting devices for guiding the fastener plates exit the machine and means for actuating said devices in timed relation by a step by step movement.

15 9. In a machine for making and driving corrugated metallic fasteners, the combination of automatic means for advancing a metallic ribbon in the direction of its length thru the machine, means for then swage-beveling and severing said ribbon into a plurality of beveled edged strips, means for then transversely corrugating said strips, means for feeding said transversely corrugated strips, means for severing a fastener of suitable length from one of said corrugated strips, means for then driving said corrugated fastener edgewise and in a direction to insert the corrugations endwise and connected mechanism by which the swaging and feeding and corrugating and severing and driving operations are performed in the order mentioned, said mechanism comprising a single shaft operatively connected with all of said means.

10. In a machine for making and driving corrugated fasteners, the combination of co-acting swagers for swage-beveling and swage-severing a metallic ribbon into strips, co-acting corrugating rolls for transversely corrugating said strips, co-acting severing knives for transversely severing a suitable length from one of the corrugated strips, co-acting spring pressed fastener holders for supporting the severed fastener preparatory to driving, a fastener driver for driving the corrugated fastener edgewise and in a direction to insert the corrugations endwise, and suitable connecting means for automatically operating the swaging, feeding, corrugating, severing and driving mechanism.

11. In a machine for making and driving corrugated metallic fasteners, the combination of automatic means for first swage-beveling and swage-severing a metallic ribbon into two strips, each strip having a sharp-cutting beveled burr-free finished penetrating edge, said penetrating edge requiring no further sharpening treatment, means for then forming transverse corrugations in the flat strips, automatic means for then severing a suitable length from one of said corrugated strips, automatic means for finally driving the severed corrugated length edgewise, and suitable operating connections by which the corrugating and cutting and driving operations are performed on each fastener in the order mentioned.

12. In a machine for making and driving serrated corrugated metallic fasteners, the combination of automatic means for first swage-beveling and swage-severing a metallic ribbon into two serrated strips, each strip having a sharp-cutting beveled serrated burr-free finished penetrating edge, said serrated penetrating edge requiring no further sharpening treatment, means for then forming transverse corrugations in the flat strips, automatic means for then severing a suitable length from one of said serrated corrugated strips, automatic means for finally

driving the severed corrugated length edgewise and in a direction to insert the corrugations endwise, and suitable operating connections by which the corrugating and cutting and driving operations are performed on each fastener in the order mentioned.

13. In a machine for making and driving corrugated metallic fasteners, the combination of means for first forming two beveled edged strips by swaging a relatively flat metallic ribbon in the direction of its length and between the longitudinal side edges thereof, means for then forming transverse corrugations in the strips, means for then cutting off a suitable length from one of said strips of corrugated metal, means for finally driving the cut length of corrugated strip edgewise and in a direction to insert the corrugations endwise, means for then guiding the other of said corrugated strips exit the machine and suitable operating connections by which the swaging and corrugating and cutting and driving operations and exit guiding of one strip are performed on the metallic ribbon and on each fastener strip in the order mentioned, said cutting means including a pair of coating severing knives, one knife being stationary and the other knife being movable, the cutting edges of which knives are longer than the transverse corrugations in the strips of corrugated metal, the said driving means including a fastener driver provided with an end portion adapted to engage the ends of the transverse corrugations of each fastener.

14. In a machine for making and discharging corrugated metallic fasteners, the combination of means for swaging a metallic ribbon into two strips having sharp-cutting beveled edges, means for corrugating said beveled strips, means for transversely severing a suitable length from each of said corrugated strips forming fasteners, means for holding the severed corrugated fasteners preparatory to discharging, driving means for discharging the fasteners edgewise exit the machine, guiding means for guiding the ribbon and strips thru the machine in fixed relation to the swaging corrugating severing and discharging means, and suitable connections by which the swaging corrugating severing and driving means are caused to function in the order mentioned, said severing means including a pair of cooperating shearing knives the cutting edges of which are longer than the combined width of the corrugated strips, said discharging means including a reciprocating head provided with a relatively thin end portion adapted to engage the fastener.

15. In a machine for making and ejecting corrugated metallic fasteners, the combination of means for first swage-beveling and severing a metallic ribbon into strips, means for then forming transverse corrugations in the strips, means for then severing a suitable length from said corrugated strips, means for ejecting the severed cut lengths of corrugated strip edgewise exit the machine, suitable operating connections by which the swaging and corrugating and severing and ejecting operations are performed in the order mentioned, spring pressed holding means adapted to engage and support the severed lengths of corrugated fastener preparatory to discharging the fastener.

16. The combination with a supporting body of metal and associated supporting parts, of a pair of integral swage-beveling and severing and spacing rolls adjustably mounted, said rolls

- adapted to impress serrated formations into metallic ribbon thereby forming strips, of a pair of corrugating rollers for corrugating strips of metal, a cutter device and cutter bed for severing one of the corrugated strips into suitable lengths and thereby forming fastening plates, devices for feeding the strip, a hammer device for driving fastener plates successively and edge-wise in the line of the corrugations, spring operated fingers for holding the fasteners in position, the driving device being arranged to receive a driving blade adapted to pass between said fingers, and means for guiding one of said strips exterior the machine.
17. In a machine for making and driving corrugated fasteners made from metallic ribbon, the combination of means for swaging two beveled edged strips from one ribbon, each strip having a swaged beveled sharp-cutting hardened edge at the penetrating end, corrugating means for forming transverse corrugations in the sharpened strips, means for severing a suitable length from one strip thereby producing a cut-to-length corrugated fastener, means for driving said fastener edgewise and in a direction to insert the corrugations endwise, means for guiding the unsevered strip exit the machine, operating connections by which the swaging and corrugating and severing and driving operations and exit guiding of one strip are performed as described on the respective strips and fastener in the order mentioned.
18. In a machine for making and discharging corrugated metallic fasteners, the combination of means for first swage-beveling and slitting a metallic ribbon into two strips, means for then forming transverse corrugations in the strips, means for then severing a suitable length from said corrugated strips, means for finally discharging the severed lengths of corrugated strips edgewise and in a direction to exit the machine.
19. In a machine for making corrugated fasteners from metallic ribbon the combination of means for swaging serrations and concurrently severing the ribbon in the direction of its length into a plurality of strips having beveled sharp cutting serrations on one edge of each of the resultant strips, means for simultaneously corrugating the strips and means for advancing the ribbon and strips in the direction of their length by a step by step movement.
20. In a machine for producing corrugated fasteners from metallic ribbon, the combination of ribbon swaging and slitting means and corrugating means operating upon said strips subsequent to the division of the ribbon into strips by said combined slitting and swaging mechanism, said swaging mechanism comprising opposed gear driven rolls each roll provided with opposed safety lands adapted to maintain the cutting edges of said swaging rolls short of contact and in vertical alignment.
21. In a machine for making corrugated fasteners from metallic ribbon, the combination of cooperating swaging means for first severing said ribbon into two strips each strip having a swaged beveled sharp cutting penetrating edge requiring no further sharpening treatment, means comprising safety lands for maintaining the opposed bevel forming cutting edges of said swaging means short of contact and corrugating means for then forming transverse corrugations in one of said sharpened strips.
22. In a machine for making corrugated fasteners the combination of means for simultaneously swaging and slitting a flat metallic ribbon producing sharp cutting beveled serrations on one edge of each of the resultant separated strips, means comprising flattening rolls for returning the swaged upset metal into the body of the strips, and means for then corrugating said serrated edged strips.
23. In a machine for producing fasteners from metallic ribbon, the combination of stock sharpening beveling hardening serrating and slitting mechanism for producing a plurality of strips, each of which is sharpened hardened and serrated at one edge thereof.
24. In a machine for producing corrugated fasteners from metallic ribbon, the combination of stock sharpening beveling hardening serrating and slitting mechanism for producing a plurality of strips, each of which is sharpened beveled hardened and serrated on one edge thereof, and means for then corrugating each strip.
25. In a machine for producing corrugated fasteners from metallic ribbon, the combination of stock sharpening beveling hardening serrating and slitting mechanism for producing a plurality of strips, each of which is sharpened beveled hardened and serrated on one edge thereof, means for then corrugating each strip and strip severing means for then transversely severing a length from said strips.
26. In a machine for producing fasteners from metallic ribbon, the combination of a succession of gear driven co-acting swaging rolls for beveling sharpening serrating and slitting a ribbon into a plurality of strips therewith producing without loss of metal sharp cutting bevels hardened and serrated on one edge of the resultant separate strips; means for corrugating the serrated edged strips.
27. In a machine for producing fasteners from metallic ribbon, the combination of a series of swaging elements for swaging beveled surfaces and serrated edges on metallic ribbon producing a plurality of strips, each of the resultant strips having beveled serrations on one edge thereof, a series of corrugating means for corrugating each strip, and guide means for guiding said corrugated strips exit the machine.
28. In a machine for making corrugated fasteners, the combination of means for swaging beveling and serrating flat metal stock, thereby producing two swage-beveled serrated edged strips without loss of metal and means for corrugating said bevel serrated strips.
29. In a machine for making corrugated fasteners, the combination of a succession of swage-beveling and swage-slitting mechanisms, co-acting duplex corrugating rolls for producing corrugations in the resulting swage-beveled strips so that the corrugations of one strip are in parallel relation and the corrugations of the other strip are in divergent relation.
30. In a machine for making corrugated fasteners, the combination of swaging means for beveling hardening serrating and slitting flat metal stock and simultaneously producing sharp cutting hardened bevels and serrations on one edge of the resultant separate strips, corrugating means comprising co-acting units for operating upon the strips, means for effecting a relative adjustment of the swaging and corrugating means to position the opposed units of said swaging means and the opposed units of said

- corrugating means with reference to each other, and strip guiding means positioned in cooperative relation to the swaging means and the corrugating means.
- 5 31. In a machine for making corrugated fasteners, the combination of stock beveling and slitting mechanism for producing a plurality of sharp swaged beveled strips from flat metal stock, corrugating mechanism embodying two 10 sets of cooperating paired rolls, each paired set of rolls provided with mated corrugations, the corrugations in one paired set of rolls being parallel with respect to the axis of the roll and the corrugations in the other paired set of rolls being 15 divergent with respect to the axis of the roll.
32. In a machine for producing fasteners from metallic ribbon, the combination of opposed stock swaging rotatable units for slitting a ribbon passed therebetween into beveled serrated 20 edged strips, said units comprising in combination integral elements for beveling serrating and slitting and cylindrical contacting lands for maintaining said beveling serrating and slitting elements of one unit short of contact with like 25 elements of the opposed unit, means for positioning the serrations of one unit in register with the serrations of the opposed unit.
33. In a machine for making and driving corrugated metal fasteners, the combination of a 30 series of coordinated elements comprising, first, ribbon guiding elements cooperating with co-acting swaging elements for guiding a metallic ribbon in the direction of its length into swaging relation with swagers adapted to swage the ribbon into strips each strip having two oppositely beveled surfaces intersecting and forming a longitudinal cutting edge positioned in the mid plane of the flat strip, said cutting edge requiring no further sharpening treatment, of corrugated elements for then forming transverse 35 corrugations in each strip, of a corrugated strip guiding element for then guiding one of said corrugated strips exit the machine, of co-acting corrugated strip severing elements for then severing the other of said corrugated strips into 40 suitable lengths forming corrugated fasteners, of spring pressed holding elements for then holding the fastener in position to receive a fastener driver element, of a fastener driver element for 45 finally driving the severed corrugated fastener edgewise and in a direction to insert the corrugations end-wise, and suitable operating connections by which the swaging, corrugating, cutting and driving operations are performed on 50 the ribbon, strip, corrugated strip and fastener in the order mentioned, including a single shaft the end of which is operatively connected by a fixed element thereon with all said elements and mechanism comprising a clutch for controlling the 55 rotation of said shaft.
34. In a machine for making toothed corrugated fasteners, the combination with means for feeding a strip of metallic ribbon, of combined swage-bevelers and swage-severers oppositely 60 positioned for operation upon the opposed faces of the metallic ribbon, means comprising concentric lands of slightly greater diameter than the swagers for adjusting the distance between the swagers, said combined swage-bevelers and 65 swage-severers having beveled cutting faces rotating in a plane at right angles to the face of the ribbon and between the longitudinal side edges thereof, corrugating elements positioned for operation upon the opposite faces of said 70 metallic ribbon subsequent to the severing of the 75

ribbon into strips, and means for cutting said strips into lengths.

35. In a machine for making and driving corrugated metal fasteners, the combination of co-ordinated means driven from a power source, comprising means for feeding a flat metal ribbon into guided relation with swaging units, means for swaging the ribbon thus fed into strips each of said strips having a beveled cutting edge on one side edge, means for corrugating the strips, 10 means for cutting off a suitable length from one of said strips forming a cut length fastener, guide means for guiding the other of said strips exit the machine, means for driving said cut length fastener edgewise and in a direction to 15 insert the corrugations endwise, suitable connections by which the feeding and swaging and cutting and driving operations are performed on each transversely corrugated fastener in the order mentioned. 20

36. In a machine for making and driving corrugated metal fasteners, the combination of co-ordinated means driven from a power source, comprising means for feeding a flat metal ribbon, means for swaging the ribbon into strips 25 each of said strips having a beveled cutting edge in the medial plane of each of the strips, i. e., in a plane midway the planes of the relatively wide faces of the strips, means for corrugating the strips, means for cutting off a suitable length 30 from one of said strips forming a cut length fastener, guide means for guiding the other of said strips exit the machine, means for driving said cut length fastener edgewise and in a direction to insert the corrugations endwise. 35

37. In a machine for making toothed fasteners the combination of coacting toothed swagers for swaging a metallic ribbon into a plurality of strips each strip having sharp cutting beveled hardened toothed edges on one edge portion 40 thereof.

38. In a machine for making fasteners the combination of a succession of paired means for swaging a metallic ribbon to sever the same into strips, means for regulating the traverse adjustment of opposed swaging elements, and means comprising contacting lands adapted to maintain said swaging means short of contact during the severance of the ribbon into strips, and means for corrugating said strips. 45

39. In a machine for making corrugated fasteners the combination of a series of swaging units comprising swaging rolls detachably secured to their respective shafts thereby to permit easy interchange with like rolls having dissimilar 55 configurations, said rolls due to their interchangeability adapted to swage bevel sharpen and sever a metallic ribbon into strips having desired configurations at the penetrating end.

40. In a machine for making corrugated 60 fasteners the combination of a series of swaging units comprising swaging rolls detachably secured to their respective shafts thereby to permit easy interchange with like rolls having dissimilar configurations, said rolls due to their interchangeability adapted to swage bevel sharpen 65 and sever a metallic ribbon into strips having desired configurations at the penetrating end, corrugating rolls detachably secured to their respective shafts to permit interchange with like 70 rolls having dissimilar configurations thereby to impart parallel corrugations or divergent corrugations to the swaged strips.
